UNITED STATES PATENT OFFICE.

JAMES WILSON, OF PUEBLO, COLORADO.

DESIGN FOR A CLEANING AND ALINING DEVICE FOR GIN AND DELINTER SAW-TEETH.

57,561.

Specification for Design.

Patented Apr. 12, 1921.

Application filed April 12, 1920. Serial No. 373,399. Term of patent 14 years.

To all whom it may concern:

Be it known that I, JAMES WILSON, a citizen of the United States, residing at Pueblo, in the county of Pueblo and State of Colorado, have invented a new, original, and ornamental Design for a Cleaning and Alining Device for Gin and Delinter Saw-Teeth, of which the following is a specification, reference being had to the accompanying drawing, forming a part thereof.

Figure 1 is a side elevation of the device, and,

Fig. 2 is an enlarged section taken on line 2—2 of Fig. 1.

I claim:—

The ornamental design for a cleaning and alining device for gin and delinter saw teeth, as shown.

JAMES WILSON.
